John J. Flanagan,
Attorney.

UNITED STATES PATENT OFFICE.

WILLIAM HOSKIN, OF DENVER, COLORADO, ASSIGNOR OF ONE-THIRD TO LED L. RICHARDSON, OF DENVER, COLORADO.

MILK-BOTTLE CARRIER.

1,377,350.

Specification of Letters Patent. Patented May 10, 1921.

Application filed April 11, 1919. Serial No. 289,418.

To all whom it may concern:

Be it known that I, WILLIAM HOSKIN, a citizen of the United States, residing at Denver, in the county of Denver and State of Colorado, have invented new and useful Improvements in Milk-Bottle Carriers, of which the following is a specification.

The present invention is directed to improvements in milk bottle carriers, and has 10 for its object to provide an article of this character so constructed that the bottle when engaged therewith will be firmly held against accidental displacement, but may be readily and quickly detached or replaced, 15 as desired.

A further object of the invention is to provide a carrier of this nature formed from a single strand of suitable wire, and having means for firmly gripping a bottle, 20 and further having means for positively holding the usual disk stopper in place.

Another object of the invention is to provide an article of this character which is exceedingly simple in construction and operation, and one which can be manufactured at a minimum cost.

Still another object of the invention is to provide a carrier which can be conveniently carried by a person with a milk bottle engaged therewith in such a manner as to 30 positively eliminate the likelihood of dropping the bottle as now frequently occurs when a bottle is carried without a holder or carrier.

With these and other objects in view, this 35 invention resides in the novel features of construction, formation, combination and arrangement of parts to be hereinafter more fully described, claimed and illustrated in 40 the accompanying drawing, in which:—

Figure 1 is a perspective view of the carrier, showing in dotted lines a milk bottle engaged therewith.

Fig. 2 is a side elevation of the carrier.

Fig. 3 is a fragmentary rear elevation.

The carrier is formed from a single strand of preferably resilient wire of suitable gage, and is bent intermediate its ends to provide an elongated handle loop 1. The 50 terminals of the handle loop terminate in vertical bars 2 which are in contacting relation, said bars in turn terminate in substantially horizontal arms 3 also in contacting relation. The arms 3 terminate in up-

wardly curved seats 4, the purpose of which 55 will appear later.

The seats 4 terminate in downwardly extending bars 5, each of which extend forwardly to provide horizontally disposed arms 6, which have their free ends flared, as 60 at 7. The arms 6 are curved longitudinally so as to conform to the contour of the usual milk bottle 8, which they are adapted to embrace.

The arms 6 terminate at their rear ends in 65 vertically disposed arms 9, which are longitudinally curved to conform to the vertical curvature of the breast of the bottle 8, which they snugly engage, and serve in conjunction with the seats 4 to positively prevent the bottle moving upwardly accidentally. The arms 9 terminate at their lower ends in convergingly arranged legs 10, which, form in effect, a pocket adapted to receive the body of the bottle therebetween, 75 and serve to limit the movement thereof laterally and rearwardly.

The bottom 11 of the carrier consists of horizontally disposed bars 12 which extend from the legs 10. The bars 12 are bowed 80 slightly upwardly and are angular in formation, and contact, thereby forming a substantially X-shaped frame for supporting the bottom of the bottle 8.

The forward ends of the bars 12 terminate 85 in vertical arms 13 having eyes 14 formed on their upper ends. The arms 13 and eyes 14 engage the bottle adjacent its bottom, and serve to prevent the same from slipping forwardly from the bottom frame, but it is 90 obvious that the bottle may be readily lifted when the neck thereof disengages the arms 6 and seats 4.

In operation, the bottle 8 is placed at an 95 inclination with respect to the carrier with its bottom resting on the bars 12, whereupon the handle loop 1 is grasped and pressure exerted thereon in an upward direction until the seats 4 are slightly elevated, which is readily accomplished since the carrier is 100 formed from resilient wire. The bottle is then rocked inwardly until the edge of the neck is directly under the seats 4, and upon releasing the pressure on the handle loop 1 the seats will move downwardly until they 105 receive the upper edge of the bottle neck, thus firmly locking the bottle in the carrier. Since the arms 6 are resilient and have their

free ends flared the neck of the bottle can readily pass therebetween until the same have firmly embraced it, and at which time the body enters the pocket formed between the legs 10. To remove the bottle from the carrier it is only necessary to grasp the handle loop 1 with one hand and with the other the body of the bottle, and upon exerting pressure on the handle loop 1 until the seats 10 4 clear the edge of the bottle neck the bottle may be easily lifted from the carrier.

What is claimed is:

1. In a bottle carrier, a bottom frame, a pair of convergently arranged legs extended upwardly therefrom, a pair of yieldable neck embracing arms disposed in a plane with the frame, and overhanging the same, a handle-loop disposed above the arms, a yieldable seat between the arms and handle-loop for engaging the upper edge of the bottle neck when a part of the body of the bottle is engaged between the legs.
2. In a bottle carrier, a bottom frame, a pair of spaced legs extending upwardly from the frame, a pair of yieldable neck embracing arms overhanging the frame, seats disposed in off-set relation thereto, and disposed above said arms, said seats being adapted to engage the upper edge of the bottle neck when the bottom thereof rests on the frame, and means for engaging the bottle to hold a portion of its body in the space between said legs.
3. A bottle carrier consisting of a single strand of resilient wire bent intermediate its

ends to provide a handle loop, horizontally disposed arms disposed below the handle loop and terminating in seats, said seats being adapted to yieldably engage the upper edge of the bottle neck, horizontal neck embracing arms below the first named arms which terminate in vertically disposed arms for engaging the breast of the bottle, the last named arms terminating in convergently arranged legs for receiving a part of the bottle therebetween, the terminals of said legs providing horizontal bars which form a bottom frame, and means on the terminals of said bars for engaging the bottle adjacent its bottom.

4. As a new article of manufacture, a bottle carrier consisting of a single strand of resilient wire bent intermediate its ends to provide a handle loop, said loop terminating in vertical bars which in turn terminate in substantially horizontal arms, said arms terminating in seats, the seats terminating in vertical bars the terminals of which extend into horizontal neck embracing arms, a bottom frame, and convergently arranged legs connecting the bottom frame and neck embracing arms.

In testimony whereof I have hereunto set my hand in presence of two subscribing witnesses.

WILLIAM HOSKIN.
